US00D781719S

(12) **United States Design Patent** (10) **Patent No.:** **US D781,719 S**
(45) **Date of Patent:** **** Mar. 21, 2017**

(54) **PACKAGING WITH ACCESSORY**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Danielle De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco (CA); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/552,923**

(22) Filed: **Jan. 27, 2016**

Related U.S. Application Data

(63) Continuation of application No. 29/499,673, filed on Aug. 18, 2014, now Pat. No. Des. 750,501, which is (Continued)

(74) *Attorney, Agent, or Firm* — Sterne, Kessler, Goldstein & Fox PLLC.

(57) **CLAIM**

The ornamental design for packaging with accessory, as shown and described.

DESCRIPTION

FIG. 1 is a front perspective view of packaging with accessory showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The shade lines in the Figures show transparency, and not surface ornamentation.

The broken lines in the figures show portions of the packaging with accessory that form no part of the claimed design.

1 Claim, 3 Drawing Sheets

Related U.S. Application Data

a continuation of application No. 29/476,534, filed on Dec. 13, 2013, now Pat. No. Des. 714,659, which is a continuation of application No. 29/431,874, filed on Sep. 11, 2012, now Pat. No. Des. 695,632.
